UNITED STATES PATENT OFFICE.

LAWRENCE W. LUELLEN, OF MOUNTAIN LAKES, NEW JERSEY.

DISPENSING APPARATUS.

1,131,255.

Specification of Letters Patent.

Patented Mar. 9, 1915.

Original application filed March 24, 1911, Serial No. 616,714. Divided and this application filed November 18, 1914. Serial No. 872,677.

To all whom it may concern:

Be it known that I, LAWRENCE W. LUELLEN, a citizen of the United States, residing at Mountain Lakes, county of Morris, State 5 of New Jersey, have invented certain new and useful Improvements in Dispensing Apparatus, of which the following, taken in connection with the accompanying sheets of drawing, is a full, clear, and concise 10 description.

My present invention relates to dispensing apparatus and comprehends a construction which is particularly adapted for containing and dispensing fragile articles such 15 as paper drinking cups. In the instance where my invention has been designed for storing and dispensing such paper drinking cups, the apparatus is made so as to support such cups in stacked, or nested relation, in 20 upright position within a dust-proof covering, which will protect or shield from contamination those portions of the cup intended to receive the contents, and for the engagement of the mouth of the user, and 25 in such a manner as will permit the withdrawal or removal of the lowermost terminal cup independent of the next succeeding cup. Thus the entire stack of cups are 30 kept in sanitary condition and may be withdrawn one by one from the apparatus as use requires.

One of the principal objects of my present invention is to make the cup reservoir independent of and removable from the cup- 35 supporting means.

In carrying out my invention it is intended that the cup will be yieldably supported in the dust proof covering or cup reservoir. The yieldability may be either 40 in the cup itself or in the device which engages it, or both the cup and the engaging device may be yieldable. Yieldability of the support or cup or both will be present and the cup will be removed without distortion 45 or damage.

This present application is a division of a certain application heretofore filed by me under date of March 24, 1911, Serial No. 616,714.

50 Referring to the accompanying drawings in which I have illustrated by way of example certain preferable specific embodiments of my invention (but without intending to limit myself to such specific embodiments) and in which like reference nu-

merals indicate like parts throughout the several views, I will proceed to describe the same in detail.

Figure 1 illustrates, partly in elevation and partly in section, one practicable embodiment of my invention. Fig. 2 is a horizontal section taken on a plane indicated by the lines 2-2 in Fig. 1 looking upwardly. Fig. 3 is an enlarged elevation, partly in section, of a modified form of the same invention; and Fig. 4 is a top plan view of the dispensing apparatus illustrated in Fig. 3, the cup reservoir and cups being removed to illustrate more clearly the construction of the cup-retaining means.

In detail, 1 indicates a suitable support illustrated as taking the form or embodiment of a portable stand which may be fastened to a table, shelf or the like.

2 indicates the base of a bracket which 75 may be suitably secured to the support 1 or fastened directly to a wall, if desired. This bracket is provided with an annular collar 3 and an inwardly-extending flange 4. Upon the flange 4 is an apertured annular cup- 80 supporting ring 5 made of yieldable material, preferably rubber. Resting upon this rubber ring 5 is the removable cup reservoir 6, preferably made of glass and normally closed at the top. The cups indicated at 7 85 are frusto-conical in form and are preferably, but not necessarily, provided with outwardly-extending rims or flanges 8. When the cups are nested the flanges of the cups will be spaced apart so that these will engage 90 individually the supporting device. The relative proportions of the apertured supporting ring 5 and the flange 8 of the paper cup are such that the flange of the cup will 95 rest upon and be supported by the rubber ring 5 in delivery position. The opening in the flange 4 is shown of a sufficient diameter to permit the flange of the cup freely to pass through it, but the opening in the rubber gasket or ring is shown of a smaller 100 diameter. When a yielding rubber ring 5 is used, it will afford an elastically-yieldable support for the bottom cup of the pile, which support will yield upon the lowermost cup of 105 the pile being pulled downwardly. The elastic ring will resume its normal position immediately after the passage through it of the flange of the cup, and assume a position where it will engage the next cup in the pile. The elasticity or yield-

110

ability of the gasket may be determined, not only by the inherent characteristics of the material of which it is made, the relative thickness, etc., but also by the relative diameters of the openings in the gasket and in the flange 4. By increasing the diameter of the flange 4 relatively to the diameter of the gasket, more yieldability will be present in the gasket, and, conversely, by decreasing the diameter of the flange 4 relatively to the diameter of the gasket opening, the yieldability of the gasket will be constricted.

In some instances it may be desirable to increase the flexibility, as it were, of the elastic gasket, in which instance the cups may be supported by a series of elastic yieldable fingers. In Figs. 3 and 4 such a device is illustrated wherein the reservoir 6 is shown supported by a ring 3 provided with an inwardly-directed flange 4, the ring being supported by an attaching device 9, which is slidable upon a standard 10 and may be secured in desired position of adjustment by means of a set screw 11. The lower end of the reservoir 6 has interposed between it and the flange 4 an elastic gasket 5 provided with a series of fingers 12 and 13. The series of fingers 12 project inwardly farther than do the fingers 13. This is for the purpose of giving an increased gripping action upon the cups 7, which cups, in this modified form of device, are shown to be unflanged. By this means, as the cup assumes its normal position in the holder, and as it is drawn out, it will be gripped at two zones, one zone being gripped by the fingers 12, and the other zone by the fingers 13.

It will be observed that the removable glass reservoir and supporting bracket afford a dust-excluding inclosure for the contained cups, and the reservoir may be conveniently removed from the bracket for the replenishment of the device with paper cups. This removable feature of my invention is important, and particularly so when the glass reservoir is permanently closed at the top.

In each instance the aperture of the cup-sustaining or supporting means (whether it be either of the rubber rings 5 of Figs. 1 or 2) is of less diameter, in part or in whole, than the greatest diameter of the cups so that the cups may be supported within the cup reservoir with the terminal cup of the stack, as well as several superposed cups projecting from and beneath the supporting bracket to be conveniently grasped individually by the hand of the user. The lowermost cup constitutes a closure for the delivery orifice of the container, and the rims of all the cups as well as their interior are maintained in strict sanitary condition.

To store and dispense unflanged cups it is only necessary to relatively proportion the supporting bracket, glass reservoir and sustaining-ring or projections, as shown in Fig.

2. During the withdrawal of an unflanged cup, the wall of the cup will be caused to slightly yield or give when passing the supporting means. This, however, will not injure the cup owing to its flexible quality. Such changes in proportion to meet particular requirements, I consider to be well within the scope of my invention as defined by the appended claims. I also wish it to be understood that while I have illustrated one useful application of my invention in several forms, in connection with paper drinking cups, my invention may, to equal advantage, be used in connection with the storage and dispensing of other articles.

Having thus described my invention, what I claim is:

1. In a cup-dispensing apparatus, the combination with a bracket provided with circumferentially arranged cup-supporting means, said cup-supporting means being adapted to engage the cup to be dispensed at a zone near its greatest diameter and support same in delivery position, a removable cup-reservoir closed at its top supported in substantially vertical position by the cup-supporting means, said reservoir having an internal diameter greater than the maximum diameter of the cup to be dispensed.

2. In a cup-dispensing device, the combination of a supporting delivery member provided with a delivery opening and supporting means for a stack of nested cups, said supporting means adapted to engage the cups successively near their greatest diameter when being withdrawn, and a cup reservoir removably supported by the delivery member, having an internal diameter greater than the maximum diameter of the cups.

3. In a cup-dispensing device, the combination with a circular delivery member provided with means for securing it in upright position and a circular delivery aperture through which the bottom of a pile of nested cups may normally project, of a vertically-disposed cup reservoir consisting of a glass tube of larger diameter than the greatest diameter of the cups and normally closed at the top, said reservoir being removable from and supported by said delivery member; and internally-projecting means adapted to engage the cups successively near their greatest diameter and to normally retain them with the bottom of the pile projecting downward through the delivery aperture and permit their withdrawal one by one by grasping the exposed portion of the bottom cup.

4. In a cup-dispensing device, the combination with an annular dispensing member having a supporting bracket and provided with a delivery aperture and a vertically-projecting annular flange, of a cup reservoir adapted to contain a pile of nested cups and consisting of a vertically-arranged glass

be normally closed at the top, said reservoir being removable from said dispensing member but normally resting thereon with its lower end within the vertical flange on said member, and internally-projecting means normally adapted to engage the bottom cup above its lower end to hold the same but to permit the bottom of said cup to project through the dispensing aperture when

it may be grasped for ready removal therefrom.

In witness whereof I have hereunto set my hand in the presence of two subscribing witnesses.

LAWRENCE W. LUELLEN.
